UNITED STATES PATENT OFFICE.

FRANK B. COLGROVE, OF SAN BERNARDINO, CALIFORNIA, ASSIGNOR OF ONE-HALF TO ARTHUR C. ALMIND, OF SAN BERNARDINO, CALIFORNIA.

DESIGN FOR A SPINNING-TOP.

49,761.

Specification for Design.

Patented Oct. 17, 1916.

Application filed January 21, 1916. Serial No. 73,482. Term of patent 14 years.

To all whom it may concern:

Be it known that I, FRANK B. COLGROVE, a citizen of the United States, residing at San Bernardino, in the county of San Bernardino and State of California, have invented a new, original, and ornamental Design for Spinning-Tops, of which the following is a specification, reference being had to the accompanying drawing, forming a part thereof.

I claim:

The ornamental design for a spinning top, as shown.

FRANK B. COLGROVE.

Witnesses:

FRANCIS E. GIRARD,
A. C. AMANS.
